UNITED STATES PATENT OFFICE.

OREL D. ORVIS, OF NEW YORK, N. Y.

STEAM-GENERATOR.

SPECIFICATION forming part of Letters Patent No. 308,429, dated November 25, 1884.

Application filed September 20, 1884. (No model.)

To all whom it may concern:

Be it known that I, OREL D. ORVIS, of the city and county of New York, in the State of New York, have invented a new and useful Improvement in Steam-Generators, of which the following is a specification.

My invention relates to those generators in which are comprised a cylinder or multitubular boiler, a drum or hollow bridge, which is placed transversely at the back of the furnace and forms the top or a part of the bridge-wall, and pipes or systems of pipes connecting the drum or hollow bridge with the steam and water spaces of the boiler proper.

My invention consists in the combination, with the boiler proper, of a conical drum or shell constituting a part of the bridge-wall, and made in the form of a frustum of a cone, a pipe or pipes connecting said drum or bridge with the steam-space of the boiler for conducting to the boiler the steam generated in said drum or bridge, and a pipe or pipes connecting the water-space of the boiler with the drum or bridge for supplying water to said drum or bridge. The conical drum may be arranged in such position that its top or upper side will be truly horizontal and its bottom or under side inclined, in which case all mud and sediment will tend to the lower end of the drum; or the drum may be arranged or set with its bottom or under side horizontal and all the inclination on the top or upper side, whereby the steam generated in the drum will be made to flow to the highest end thereof.

It is very desirable, however, to afford provision both for the movement of mud and sediment toward one end of the drum and for the flow of steam to the end of the drum; and to this end my invention also consists in the combination, with a boiler proper, of a conical drum or shell constituting a part of the bridge-wall, and made in the form of a frustum of a cone, and having its top and bottom both inclined, and pipes connecting the boiler proper and said drum or hollow bridge, and providing for the flow of water from the boiler proper to the drum or bridge and the flow of hotter water and steam from the drum or bridge to the boiler proper.

The invention also consists in the combina-

tion, with a boiler proper, of a hollow bridge or drum constituting a part of the bridge-wall, a large pipe or water-leg, depending from the bottom of the boiler near its rear end and connected with the said hollow bridge or drum, and systems of pipes also extending from the bridge or drum and connected with the upper portion of the boiler near the front end thereof, and preferably the steam-space therein.

The invention also consists in the combination, with a boiler proper, of a hollow bridge or drum constituting a part of the bridge-wall, a large pipe or water-leg depending from the bottom of the boiler near its rear end, and connected with said hollow bridge or drum, systems of pipes connecting the bridge or drum with the upper portion of the boiler, a blow-off pipe leading from said bridge or drum, and a pipe leading from the lower end of the depending pipe or water-leg to the blow-off pipe.

The invention also consists in a combination, with a boiler proper, of a hollow bridge or drum constituting a part of the bridge-wall, a large pipe or water-leg depending from the bottom of the boiler near the rear end, pipes extending laterally from opposite sides of the water-leg and extending to the bridge or drum near opposite ends thereof, the water-leg being prolonged below the laterally-extending pipes, systems of pipes connecting the hollow bridge or drum with the front portion of the boiler, a blow-off pipe leading from the bridge or drum, and a pipe leading from the lower end of the large pipe or water-leg to the blow-off pipe.

The invention also consists in the combination, with the boiler proper, the hollow bridge or drum, the depending water-leg, and the pipes extending laterally therefrom and connected with the bridge or drum, all as hereinabove described, of systems of pipes connecting both the bridge or drum and the pipes extending to the bridge or drum from said water-leg with the front portion of the boiler.

The invention also consists in other combinations of parts, hereinafter particularly described, and pointed out in the claims.

In the accompanying drawings, Figure 1 is a side view of my improved generator and a

sectional view of the brick-setting thereof, the generator being represented as it would appear with one side wall entirely removed. Fig. 2 is a transverse vertical section on the irregular plane of the dotted line xx , Fig. 1. Fig. 3 is a transverse vertical section on the plane of the dotted line yy , Fig. 1, looking rearward. Fig. 4 is a transverse vertical section on the plane of the dotted line zz , Fig. 1, looking forward. Figs. 5 and 6 are transverse vertical sections similar to Fig. 3, showing different arrangements of the hollow bridge or conical drum which constitutes a part of the bridge-wall; and Fig. 7 is a side elevation 15 of a generator with the side wall removed as in Fig. 1, showing a different arrangement of the systems of pipes which connect the hollow bridge or conical drum with the front portion of the boiler proper.

20 Similar letters of reference designate corresponding parts in all the figures.

In all figures of the drawings, A designates the boiler proper, which is here shown as multitubular, and is provided with the usual 25 steam-dome, A', and with lugs or knees a, whereby it is supported on the side walls, B B, of the brick setting.

C designates the furnace, and C' the ash-pit, which are provided with the usual doors, b b', 30 and D is the grate, at the back of which is the bridge-wall E, the top portion of which consists of a hollow bridge or drum, E'. This hollow bridge or drum has one distinguishing characteristic, namely, that it is conical or 35 made in the form of the frustum of a cone, being considerably smaller in diameter at one end than at the other.

Behind the bridge-wall E is the combustion chamber or space F, to which access may be 40 had by a door, c, in the rear wall, B', of the setting. After passing forward through the tubes of the boiler the products of combustion enter the breeching or front connection, G, and thence pass rearward on top of the 45 boiler through the flue H and make their exit at the opening H', which leads to the smoke pipe or chimney. Near the rear end of the boiler a large pipe or water-leg, I, depends from the bottom thereof.

50 Referring now more particularly to Figs. 1, 2, 3, 4, it will be seen that the frustum of a cone or conical drum, E', which forms the top portion of the bridge-wall E, is set with its top or upper side horizontal from end to end, and 55 with its taper all on the bottom or under side.

Any sediment or mud will then tend toward the larger end of the drum, from which extends the blow-off pipe d, and may be got rid of by blowing off. The blow-off pipe d extends to the front of the boiler, as here shown, and is there provided with the usual blow-off valve or cock d'. As here shown, the depending pipe or water-leg I contains a cross-fitting, I', and from opposite lateral branches 65 thereof proceed pipes e, which are extended forward and connected with the bridge or

conical drum E' near its two ends, as is shown in Figs. 1 and 4. The water-leg I is prolonged beyond the pipes e, and with its lower end is connected a blow-off pipe, d², which enters the blow-off pipe d near the junction of the latter with the drum E'. By means of the single blow-off connection d, I thus provide for blowing off both the bridge-drum E' and the boiler proper, A, and the conical drum 70 enables me to provide for blowing off the deposit at the larger end of the drum by setting the drum with its inclination on the under side and permits of the upper side of the drum being horizontal, thus giving the same height 75 of bridge-wall at one end as the other. This result cannot be attained with a cylindric drum set in an inclined position, for in that ease the top or upper side of the drum must have the same inclination as the bottom or 80 under side thereof. The larger end of the drum E' projects through one side wall, B, of the generator, and is exposed on the outside 85 thereof, and the smaller end of said drum projects sufficiently into the opposite side wall 90 to be afforded ample support. At the larger end the drum E' is provided with the proper man-hole f, and the feed-pipe f' is also shown as entering that end of the said drum.

At the front of the boiler A, and on each 95 side thereof, are headers J, which are connected at their upper ends by pipes g with the steam-space or upper part of the boiler at the front thereof. As here shown, the headers are composed of cross-fittings united by 100 nipples, and from each of them extend pipes or tubes J* J' J² J³ J⁴ J⁵ J⁶. The number of these pipes may be varied, as may be desired. As here shown, the lowermost pipe, J*, of each header extends direct to the drum E', near the 105 end thereof. The next two pipes, J' J², are connected by suitable fittings with each other and with the pipe J*. The pipe J³ has a downwardly-presented terminal portion, J³*, and is connected with the top of the drum E, and 110 the pipes J⁴ J⁵ J⁶ have downwardly-presented terminal portions J⁴* J⁵* J⁶*, and are connected with suitable T-fittings, e*, in the two laterally-extending pipes e. The several pipes J* J' J², &c., are set at a considerable inclination 115 as will be observed, and hence the steam and highly-heated water are afforded an easy upward passage through them to the headers J, and thence through the headers and pipes g into the boiler proper, wherein the steam 120 readily separates from the highly-heated water. It will be understood that a system of pipes J* J' J², &c., with header J is employed on each side of the boiler A.

I have here shown the branches of the cross-fittings in the headers J which are opposite the pipes J' J², &c., as closed by plugs, *, and by removing these plugs a brush may be introduced through the pipes J' J², &c., for clearing them of scale.

125 From the foregoing description it will be understood that the system of pipes J* J' J²,

&c., being exposed to the hottest part of the fire, the circulation of water will be downward through the large pipe or water-leg I at the rear end of the boiler, where the heat is less intense, thence through the pipes e and to the drum E', and from the drum the water which enters from the pipes e, together with the feed-water and steam, pass through the pipes J* J' J² J³ direct to the headers J, and thence into the steam space of the boiler. The pipes J* J² J³ and J' J⁵ also offer an avenue of escape to the headers J of any water in the pipe e which tends to take that course and any steam generated in the pipes e or the pipes leading therefrom. The pipes J³ also serve for the passage of steam and most-highly-heated water from the drum E' to the headers J and thence to the steam-space of the boiler. The direct heat to which the portion of the bottom of the boiler over the fire is exposed prevents the mud or sediment from there settling, and it settles in larger quantity near the rear end of the boiler. The water at the bottom of the boiler near the rear end is naturally cooler than it is over the fire, and hence the location of the large water-leg I at the bottom of the boiler near the rear end thereof is advantageous, because the cooler water in its natural circulation downward through the water-leg I carries with it the mud and sediment which has settled near the rear end of the boiler. The transverse section shown in Fig. 5 corresponds in all respects to that in Fig. 3, except that in Fig. 5 the bridge-drum E' has a greater taper than in the figure before described, and has its axis nearly or quite horizontal, thereby making an inclination at both the upper and lower sides or top and bottom thereof. Thus I provide not only for the movement of mud and sediment to the larger end of the drum, where the blow-off pipe d connects, but I also provide for the passage of steam toward the larger end of the drum, from which it escapes through one of the systems of pipes J* J' J², &c.

Fig. 6 represents the conical drum E', set with its bottom or under side approximately horizontal and the inclination at the upper side or top, thus providing for the flow of steam generated in the drum to one end thereof, and whence it escapes by one of the systems of pipes J* J' J², &c.

In all respects Fig. 7 corresponds with the figures before described, save that none of the pipes which connect with the headers J are connected with the pipes e.

I have here shown six pipes, J* J' J² J³ J⁴ J⁵, and a similar system is upon each side of the generator. The lowermost pipe, J*, extends from the bottom of the header J direct to the drum E', and the pipes J' J² are connected, as clearly shown, with each other and with the pipe J*. The pipes J³ J⁴ J⁵ are connected by a suitable header, J', with the top of the drum E'. In the operation of this generator the water passes downward through the

large pipe or water-leg I and thence through the pipes e to the drum E', and steam which is generated in the drum or which enters it through the pipes e has a direct avenue of escape through the headers J' and pipes J³ J⁴ J⁵ to the headers J and the steam-space of the boiler proper. Highly-heated water also passes from the drum E' through the pipes J* J', &c., to the header J.

It is obvious that the number of the pipes J* J' J², &c., may be varied as may be desired, as may also the size of the pipes.

In both arrangements of pipes shown in Figs. 1 and 7 the several pipes J* J', &c., are all inclined in the same direction, and hence water and steam pass through them separately and direct to the headers J; or, in other words, the passages for the steam and water are not circuitous as when a number of pipes are arranged at reverse inclinations and connected so as to compel the water and steam to traverse a long and circuitous passage in passing from the bridge-drum to the boiler proper. Hence the circulation is much more vigorous and effective.

What I claim as my invention, and desire to secure by Letters Patent, is—

1. The combination, with the boiler proper, of a conical drum or shell constituting a part of the bridge-wall and made in the form of a frustum of a cone, and pipes connecting said hollow bridge or drum with the steam and water space of the boiler proper, substantially as and for the purpose herein described.

2. The combination, with the boiler proper, of a conical drum or shell constituting a part of the bridge-wall and made in the form of a frustum of a cone set with an inclination at its under side, pipes connecting said conical bridge or drum with the steam and water spaces of the boiler proper, and a blow-off pipe leading from the larger and lower end of said bridge or drum, substantially as and for the purpose herein described.

3. The combination, with the boiler proper, of a conical drum or shell constituting a part of the bridge-wall and made in the form of a frustum of a cone and set with an inclination at both top and bottom, pipes connecting said conical bridge or drum with the steam and water spaces of the boiler proper, and a blow-off pipe leading from the larger and lower end of said bridge or drum, substantially as and for the purpose herein described.

4. The combination, with the boiler proper, of a hollow bridge or drum constituting a part of the bridge-wall, a large pipe or water-leg, I, depending from the bottom of the boiler near the rear end and connected with the said hollow bridge or drum, and systems of pipes extending from the said bridge or drum, and connected with the upper portion of the boiler near the front end thereof, whereby provision is afforded for the circulation of water from the rear part of the boiler down the said water-leg to the bridge-drum, and from said

drum through the systems of pipes into the front part of the boiler, substantially as herein described.

5. The combination, with a boiler proper, of a hollow bridge or drum constituting a part of the bridge-wall, a large pipe or water-leg depending from the bottom of the boiler near its rear end and connected with said hollow bridge or drum, systems of pipes connecting 10 said bridge or drum with the upper portion of the boiler, a blow-off pipe leading from said bridge or drum, and a pipe leading from the lower part of the depending pipe or water-leg to said blow-off pipe, substantially as 15 herein described.

6. The combination, with the boiler proper, of a hollow bridge or drum constituting a part of the bridge-wall, a large pipe or water-leg depending from the bottom of the 20 boiler near its rear end, pipes extending laterally from the water-leg and leading to the bridge or drum near opposite ends thereof, the water-leg being prolonged below said laterally-extending pipes, pipes connecting the 25 hollow bridge or drum with the front portion of the boiler, a blow-off pipe leading from the hollow bridge or drum, and a pipe leading from the lower end of said water-leg to the blow-off pipe, substantially as herein 30 described.

7. The combination, with the boiler proper, of a hollow bridge or drum constituting a part of the bridge-wall, a water-leg depending from the bottom of the boiler near its rear 35 end, pipes extending laterally from the water-leg and connected with the bridge or drum, and systems of pipes connecting the bridge or drum and the pipes leading thereto from

the water-leg with the front portion of the boiler, substantially as herein described. 40

8. The combination, with the boiler proper, A, of the hollow bridge or drum E, made conical or in the form of the frustum of a cone, the depending water-leg I, the pipes e, extending from the water-leg to the bridge or 45 drum, pipes J* J', &c., leading forward from the front and top of the said conical bridge or drum, and headers J, receiving the pipes J* J', &c., and connected with the upper front part of the boiler, substantially as herein 50 described.

9. The combination, with the boiler proper, A, of the hollow bridge or drum E', pipes for supplying water thereto from the boiler, systems of pipes J* J' J², &c., leading from the 55 hollow bridge or drum, all at an upward inclination toward the front of the boiler, headers J, receiving the forward ends of said inclined pipes, and removable plugs in said headers opposite said inclined pipes, substantially as 60 herein described.

10. The combination, with the boiler proper, A, of the hollow bridge or drum E', the depending water-leg I, the pipes e, leading from said water-leg to said bridge or drum, systems 65 of pipes J* J' J² J³ J⁴, &c., extending from the bridge or drum E' and said pipes e, and all having an upward inclination toward the front of the boiler, and headers J, receiving said inclined pipes, and connected with the 70 upper part of the boiler, substantially as herein described.
